United States Patent Office.

CHARLES V. WOERD, OF WALTHAM, ASSIGNOR TO AMERICAN WATCH COMPANY, OF BOSTON, MASSACHUSETTS.

Letters Patent No. 90,620, dated May 25, 1869.

LATHE FOR GRINDING AND POLISHING PIVOTS OF WATCH-WORK.

The Schedule referred to in these Letters Patent and making part of the same.

To all whom it may concern :

Be it known that I, CHARLES V. WOERD, of Waltham, in the county of Middlesex, and State of Massachusetts, have invented Improvements in Lathes for Grinding and Polishing Pivots, Staffs, and other Watch-Work; and I do hereby declare that the following, taken in connection with the drawings, which accompany and form part of this specification, is a description of my invention, sufficient to enable those skilled in the art to practise it.

The machine upon which my improvements are based, is essentially a lathe, adapted either to chucking-work, or to mounting it upon centres, provided with a rotating polishing-wheel, to be supplied with fine abrasive powder, said wheel being so arranged, that by changes in its position, it can be brought to operate upon the rotating body, to be ground to any required size, or to be polished, and can also be brought against revolving laps or grinders, by which its acting-surfaces and angles are kept perfectly true, so as to produce correct results in grinding and polishing.

Figure 1, of the drawings, represents, in front elevation, a machine embodying my invention;

Figure 2 showing the same in plan.

On a common bed-piece, *a*, are arranged stands, *b* *d*, the stand *b* sustaining a lathe-bed, *e*, the stands *c* and *d*, respectively, supporting bearings, in which rotate the arbors of the grinding lap-wheels *f* and *g*.

The lathe-bed is provided with a head-stock, *h*, having a rotating arbor, *i*, turned by a belt operating on the pulley *j*, one end of the arbor being adapted to receive centres or chucks, according to the requirements of the pieces to be rotated by the lathe. This head-stock is of peculiar construction, constituting one part of my invention.

In lug *h*, integral with or fixed to the head-stock *h*, are formed bearings, to receive the shaft *l*, the axis of which is parallel with the axis of the arbor *i*.

On one end of shaft *l* is fixed an arm, *m*, as shown, which bears the still or dead-centre of the lathe, the other end of shaft *l* having fixed thereon an arm, *n*, which fits upon a guide-pin, *o*, secured in the head-stock parallel with the axis of its arbor *i*, so that by sliding the shaft *l* in its bearings, the still centre can be brought near to or can be removed from the revolving centre placed in the end of the arbor, and thus pieces of any length, adapted to the structure of the lathe, can be pivoted on the lathe-centres, the setscrew *p*, operating on shaft *l*, serving to fix and hold the centres at the requisite distance apart.

For chucking-work, I remove the head-stock *h*, and replace it with another head-stock, similar, except that it is provided, at the end of arbor *i*, with the usual provisions for receiving chucks, and is without the dead-centre bearing-attachment.

This construction and arrangement is lighter, more compact, cheaper, and more accurate than is the common arrangement of the dead-centre in a separate tail-stock piece, which is now used, and it enables me to make use of the space on the lathe-bed, usually occupied by a tail-stock, for the attachment of the stand *p*, on which my rotating, polishing, or grinding-wheel *q* is mounted.

A swinging frame, *r*, is pivoted at one end to the stand *p*, the arbor *s*, of the polishing-wheel *q*, being mounted in bearings formed in the other end of the frame *r*, there being on the arbor a belt-pulley, *t*, by which rapid rotation is given the polisher *q*.

This polisher is made as the frustum of a cone, and of soft steel, and its operating-faces are ground perfectly true by being brought into contact, as often as may be required, with the rotating grinding-wheels, or laps *f* and *g*.

Those who are acquainted with the extreme minuteness of many of the pivots of a train of watch-gearing, will appreciate the absolute necessity for mathematical exactness in form and movement of polishing-wheels which are brought to bear upon them, to impart to them the exact sizes required, and to give to them the high degree of smoothness and finish needed to make them run properly in fine watch-movements.

The wheel *q* is fixed to its arbor, and, being ground thereon, will rotate with exactness so long as the arbor fits in its bearings. It is not found practical to remove the wheel from its arbor, or the arbor from its bearing, to grind the wheel, and then to replace it on them, and then have the wheel rotate with the exactness requisite.

Besides, it is necessary frequently to retouch or regrind the polishing-wheel *q*, so as to preserve the accuracy and sharpness of the angle made at the junction of its two operative-faces, as the angle gets dulled or worn very quickly in its use.

The drawings show, with accuracy and clearness, the manner of mounting and rotating the grinding-laps, so that it is unnecessary to burden this specification with a description of so simple a mechanism.

The laps themselves may be made of any suitable abrasive material, or compound.

Their form is that of short cylinders, affixed to heads or disks, by which they are secured on their arbors, the operative-faces of the laps being the ring-ends of the cylinders, which revolve in planes.

The lap *g* can be adjusted by endwise-movement of its shaft, so as to come into contact with and grind the cylindrical surface of the polisher *q*, as it wears away.

The lap *f*, which grinds the face of the polisher to a plane, may have a similar provision, though not absolutely necessary, as the arbor of the polishing-wheel

may be slid back and forth in its bearings, either to meet the lap g , or to perform its functions on the pieces in the lathe, to be ground and polished thereby.

When staffs, and other parts of watches, or similar small work, require to be ground, or polished on a taper, then the periphery of the wheel g must be ground to correspond to the taper to be produced. This is effected by so arranging the head which has the bearings for the arbor of the lap g , that the axis of said arbor may be set to any desired angle with reference to the arbor s of the polishing-wheel. To effect this, the top of the support d is extended into a large plane surface, u , to which the head v , which forms the bearings for the arbor of the lap g , is pivoted at a point under the grinding-face of the lap, and in a vertical plane passing through the axis of said arbor. When the head v is moved upon its pivot to the place requisite to give the proper angle or taper to the periphery of the wheel g , it is clamped or fastened by any suitable means.

To grind to a given size the diameters of any chucked work, not requiring the use of the still, or dead, or back-centre, I make use of the following device:

I place in a post, w , which may be secured in position as shown in the drawings, a flat-surfaced diamond, or other material, of the requisite hardness, and adjust its height above the axial line of the arbor i ,

to the radius of the size to which it is required to finish the work rotating with the lathe.

The position of the diamond, which is denoted by x , is such as to come beyond the end of the piece to be ground, but in the path of the peripheral grinding-face of the wheel g .

It will be seen that the wheel will grind until its swinging movement is stopped by abuttal of its peripheral grinding-face on the diamond. Thus, pivots, or other small, short cylinders may be ground and polished in numbers to the same diameters.

I claim, in combination with the head-stock of a lathe, a shaft, or slide, l , provided with a back-centre bearing-piece, m , and a guide, n , or its equivalent, substantially as described.

Also, the combination, with a lathe, of a swinging frame, or bearing, a polishing-wheel, and a grinding-lap or laps, arranged to operate substantially as described.

Also, the combination, with a polishing-wheel, of a gauging-stop, arranged to operate substantially as described.

CHAS. V. WOERD.
